END STOP MEMBER FOR SEPARABLE FASTENERS

Erich Wittenberg, Berlin-Schoneberg,
Germany

Application September 11, 1937, Serial No. 163,331

6 Claims. (Cl. 24—205)

The present invention relates to separable fasteners of the slider operated type and more particularly to end stop members with which the stringers of such fasteners are provided for limiting the movement of the slider.

The stop members with which the present invention is particularly concerned are arranged on the stringers to limit movement of the slider in the stringer closed position of the latter whereby to prevent the slider from moving off the stringers. When the stop members are of the type which enter into the slider channels, in the stringer closed position of the slider, they should be positioned on the stringers so that they may readily enter within the slider channels and also to permit the free movement of the slider in a direction to unmash the interlocking elements as well as in the direction of stringer closed position. One object of the present invention, therefore, is to provide end stop members with means for facilitating the correct positioning of said members laterally of the stringers.

In securing the stop members to the stringers, the opposed walls or wings of said members are pressed toward each other in clamping engagement with the corded or beaded edges of the stringers. Stop members of the construction heretofore utilized are objectionable because when too much pressure is applied to the stop members in clamping them on the stringers the beaded edges of the latter are frequently crushed resulting in an insecure attachment of the stop members. Another object of the present invention is to eliminate this disadvantage and for that purpose to provide the stop members with means to limit the movement of the opposite walls or wings of the stop members toward each other in securing the stop members to the stringers.

Another object of the invention is to provide the stop members with means for improving the securing of the stop members to the stringers.

A further object of the invention is generally to improve the construction of end stop members whereby to facilitate their attachment to the stringers and to position them correctly so as not to interfere with the operation of the slider in the movement of the latter to either stringer closing or stringer opening positions.

The above objects of the invention and other objects which might hereinafter appear will be clearly understood from the following description considered with reference to the accompanying drawing.

In the drawing:

Fig. 1 is a fragmentary plan view of a separable fastener provided with end stop members embodying the present invention;

Fig. 2 is a fragmentary plan view, on an enlarged scale, of one of the stringers provided with an end stop member of the present invention, said

stop member being shown partly in elevation and partly in section;

Fig. 3 is a sectional view on the line 3—3 of Fig. 2;

Fig. 4 is an enlarged perspective view of one of the stop members before the latter is attached to the stringer;

Fig. 5 is a view of the open side of the stop member before the latter is attached to the stringer.

Referring now more particularly to the drawing, the fastener 10 comprises, as usual, a pair of stringers 12 having confronting corded or beaded edges 14 to which the interlocking elements 16 are secured. A slider 18 of any suitable construction is movable longitudinally of the stringers in engagement with the interlocking elements 16 for meshing and unmashing the latter in closing and opening the fastener. End stop members 20 are secured to the stringers at the ends of the rows of interlocking elements for limiting the movement of the slider in stringer closed position.

The end stop members are made of suitable sheet metal and as here shown are U-shaped. The end stop members of this construction comprise opposed parts, here shown as walls or wings 22 disposed substantially at right angles to and connected by an integral end part or inner wall 24 which is crowned or curved longitudinally, i. e., in a direction of the length of the stringers. At each end of the stop member there is provided a positioning and compression limiting element 26 which is disposed between the opposed wings 22. Elements 26 are integral with and project from the ends of inner wall 24 and are disposed wholly within the channel of the stop member. The free ends 28 of said elements terminate a substantial distance inwardly of the outer edges 30 of the wings 22. When the stop member is attached to the stringer the free ends 28 of elements 26 engage the corded edges 14 and thus position the stop member correctly laterally of the stringers. Also when the walls 22 are compressed for securing the stop member to the stringer the elements 26 limit the movement of the walls 22 toward each other and thus prevent crushing of the beaded or corded edges of the stringers.

Opposed inwardly pressed ribs 32 are formed in the walls 22 for gripping the corded edges of the stringers when the end stop members are clamped thereon. Accordingly, the arrangement is such that when the opposed walls 22 are compressed to the limit allowed by the elements 26 the ribs 32 extend slightly inwardly beyond the elements 26 for gripping the corded edges of the stringers.

As illustrated in the drawing, the end stop members 20 are correctly positioned on the stringers when the outer surface of wall portion 60

- 24 is substantially in alignment with the outer ends of the interlocking elements 16 and when the free ends 30 of walls 22 are in alignment with the inner ends of said interlocking elements.
- 5 When the slider is in extreme stringer closing position said end stop members 20 are positioned preferably completely within the slider channels, at the wider end of the slider and hence are not visible in that position of the parts, al-
- 10 though it is within the scope of the present invention to provide stop members which are only partially disposed within the slider channels when the slider is in extreme stringer closing position.
- Thus, it is seen that the end stop members constructed as herein shown and described are well adapted to accomplish the several objects of the present invention. It will be understood, however, that the construction may be modified in certain respects without departing from the underlying idea of the invention. Therefore, I do not wish to be limited precisely to the construction herein shown or described, except as may be required by the appended claims considered with reference to the prior art.
- 15 Having thus described my invention, what I claim and desire to secure by Letters Patent is:
1. An end-stop for the slider of separable fasteners of the type comprising opposed stringers provided with interlocking elements operated by said slider, said end-stop comprising a member having opposed spaced wings and an inner wall defining a channel, and two members, one at each end of the channel and each having an edge disposed between said inner wall and the edges of the opposed wings, said edges of said two members being spaced equally from said inner wall and in position to be engaged by the edge of the stringer received in said channel thereby to position the end-stop member laterally of the stringer.
2. An end-stop for the slider of separable fasteners of the type comprising opposed stringers provided with interlocking elements operated by said slider, said end-stop comprising a member having opposed spaced wings and an inner wall defining a channel, and two members, one at each end of the channel and each having an edge disposed between said inner wall and the edges of the opposed wings, said edges of said two members being spaced equally from said inner wall and in position to be engaged by the edge of the stringer received in said channel thereby to position the end-stop member laterally of the stringer, said two members extending into said channel and each being free from direct connection with at least one of said opposed wings whereby the latter can be compressed toward each other for gripping the opposite sides of the stringer, said two members serving to limit the movement of said opposed wings toward each other when the stop-member is clamped onto the stringer.
3. An end-stop for the slider of separable fasteners of the type comprising opposed stringers provided with interlocking elements operated by said slider, said end-stop comprising a member having opposed spaced wings and an inner wall defining a channel in which the edge portion of the stringer is received when the end-stop is attached thereto, said spaced wings terminating in edges spaced from said inner wall, and a member projecting from each end of said inner wall toward said edges of the opposed wings, said projecting members terminating in edges disposed

between said inner wall and said edges of the opposed wings in equi-spaced relation from said inner wall in position to be engaged by the edge of the stringer thereby to position the end-stop member laterally of the stringer.

4. An end-stop for the slider of separable fasteners of the type comprising opposed stringers provided with interlocking elements operated by said slider, said end-stop comprising a member having opposed spaced wings and an inner wall defining a channel in which the edge portion of the stringer is received when the end-stop is attached thereto, said spaced wings terminating in edges spaced from said inner wall, and a member projecting from each end of said inner wall toward said edges of the opposed wings, said projecting members extending into said channel and being free from direct connection with said wings and spaced from the inner surface of at least one of said wings whereby the latter can be compressed toward each other for gripping the opposite sides of the stringer, said projecting members serving to limit the movement of said wings toward each other when the stop-member is clamped onto the stringer.

5. An end-stop for the slider of separable fasteners of the type comprising opposed stringers provided with interlocking elements operated by said slider, said end-stop comprising a member having opposed spaced wings and an inner wall defining a channel in which the edge portion of the stringer is received when the end-stop is attached thereto, said spaced wings terminating in edges spaced from said inner wall, and a member projecting from each end of said inner wall toward said edges of the opposed wings, said projecting members terminating in edges disposed between said inner wall and said edges of the opposed wings in equi-spaced relation from said inner wall in position to be engaged by the edge of the stringer thereby to position the end-stop member laterally of the stringer, said projecting members extending into said channel and spaced from the inner surface of at least one of said wings whereby the latter can be compressed toward each other for gripping the opposite sides of the stringer, said projecting members serving to limit the movement of said wings toward each other when the stop-member is clamped onto the stringer.

6. An end-stop for the slider of separable fasteners of the type comprising opposed stringers provided with interlocking elements operated by said slider, said end-stop comprising a member having opposed spaced wings and an inner wall defining a channel in which the edge portion of the stringer is received when the end-stop is attached thereto, said spaced wings terminating in edges spaced from said inner wall, and a member projecting from each end of said inner wall toward said edges of the opposed wings, said projecting members extending into said channel and being free from direct connection with said wings and spaced from the inner surface of at least one of said wings whereby the latter can be compressed toward each other for gripping the opposite sides of the stringer, said projecting members serving to limit the movement of said wings toward each other when the stop-member is clamped onto the stringer and inwardly projecting opposed ribs formed on said wings for gripping the stringer therebetween when the end-stop is clamped thereon.
